UNITED STATES PATENT OFFICE

WALTER E. SMITH, OF PROVIDENCE, RHODE ISLAND, ASSIGNOR TO KENNEY MANUFACTURING COMPANY, OF CRANSTON, RHODE ISLAND, A CORPORATION OF RHODE ISLAND

DESIGN FOR AN END ORNAMENT FOR DRAPERY RODS OR THE LIKE

Application filed July 10, 1929. Serial No. 31,087. Term of patent 7 years.

To all whom it may concern:

Be it known that I, WALTER E. SMITH, a citizen of the United States, residing at Providence, in the county of Providence and State of Rhode Island, have invented a new, original, and ornamental Design for End Ornament for Drapery Rods or the Like, of which the following is a specification, reference being had to the accompanying drawing, forming part thereof.

Figure 1 is a face view of an end ornament for drapery rods or the like, showing my new design, and Figure 2 is an edge view thereof.

I claim:

The ornamental design for an end ornament for drapery rods or the like, as shown.

WALTER E. SMITH.
